SHEET PINNING MACHINE

Joseph E. Higgins, Grand Island, Nebr.

Application June 22, 1932. Serial No. 618,797

9 Claims. (Cl. 1—46)

The invention aims to provide a rather simple and inexpensive, yet an efficient and reliable hand-actuated machine for pinning sheets of paper or sheets of other material together.

5 A base is provided upon which to rest the superposed sheets, a lever extends over this base and is mounted upon it, said lever being provided with a pin hopper, a slide is employed to feed pins from the hopper to a pin receiver, co-acting means are provided on the lever and base for imparting an arched formation to portions of the sheets, and provision is made for forcing a pin from the pin receiver through the arched formation or crimp of the sheets.

15 Further objects are to provide novel construction to prevent clogging of the pin outlet from the hopper; to provide novel means preventing movement of the pin forcing plunger into the pin receiver until the pin is properly positioned in the latter; to prevent return of the feed slide to receive another pin, if the pin previously positioned in the pin receiver has not been forced from the latter; and to provide a novel relation of lever fulcrum and slide pivot for operating the 25 slide when the lever is operated.

With the foregoing in view, the invention resides in the novel subject matter hereinafter described and claimed, description being accomplished by reference to the accompanying drawings.

Fig. 1 is a top plan view.

Fig. 2 is a longitudinal section on line 2—2 of Fig. 1, showing the normal relation of parts.

Fig. 3 is a duplicate of Fig. 2 with the exception that it shows the relation of elements when the lever is depressed to crimp the superposed sheets in readiness for forcing a pin through the crimp.

Fig. 4 is a transverse sectional view on line 4—4 of Fig. 3, the pin forcing plunger being in its normal retracted position.

Fig. 5 is a duplicate of Fig. 4 with the exception that it illustrates the manner in which the plunger forces the pin through the crimped portions of the superposed sheets.

Fig. 6 is a transverse sectional view on line 6—6 of Fig. 3.

While only one form of construction has been selected for illustration and will be rather specifically described, it is to be understood at the outset that numerous variations may be made within the scope of the invention as claimed.

The numeral 10 denotes an appropriate horizontal base provided at one end with two laterally spaced upstanding posts 11. A substantially

horizontal lever 12 extends over the base 10 and is provided at one end with an operating handle 13, said lever having two side arms 14 which extend to the end of said lever opposite said handle 13, said side arms 14 having their edges presented upwardly and downwardly, respectively. These arms 14 are fulcrumed to the upper ends of the posts 11 upon a suitable horizontal bolt or the like 15, and appropriate spring means 16 is provided to normally swing the entire lever 12 upwardly to the position of Fig. 2.

Fixedly mounted between the arms 14, is a pin hopper 17 having a pin outlet slot 18 in its bottom. Secured between the arms 14 under this hopper bottom and spaced downwardly a slight distance therefrom, is a pin receiver 19 which is preferably in the form of a plate having a groove 20 spaced forwardly from the slot 18 and opening upwardly. At the ends of this groove 20, the side members 14 of the lever 12 are formed with a plunger guiding opening 21 and a pin guiding opening 22, the latter not only extending through one of said side members but opening through the lower edge thereof. A pin feeding slide 23 is slidably received between the bottom of the hopper 17 and the pin receiver 19, and the rear end of this slide is pivoted at 24 between the lower ends of the posts 11, the pivotal axes of the fulcrum 15 and the pivot 24 being parallel and vertically spaced. By this relation of axes, when the lever 12 is depressed from the position of Fig. 2 to that illustrated in Fig. 3, the slide 23 will be moved forwardly. This slide is provided with a pin-receiving slot 25 and when this slot passes under the slot 18, it receives a pin from the latter, slot 25 being only of a size to receive one pin at a time. The slot 25 moves the received pin forwardly and drops it into the groove 20, and when the lever 12 reaches the limit of its descent, the pin is forced from this groove through the superposed paper sheets, as will be hereinafter more fully explained.

A hand-actuated plunger 26 is provided to force the pin from the groove 20. In the present showing, one end of this plunger is carried by an appropriate slide 27 engaged with a slotted guide arm 28 which projects laterally from the lever 12, the other end of said plunger being received in the opening 21 as shown in Fig. 4. By inwardly forcing upon the slide 27, the plunger is projected longitudinally through the groove 21 thereby driving the pin almost entirely through the opening 22 as seen in Fig. 5. Any desired means may be employed for returning the plunger after operation thereof. For this purpose, I have illustrated a spring-actuated arm 110

29 pivoted at 30 to a lug 31 projecting laterally from one of the side arms 14 of the lever 12.

5 Provision is made to prevent projection of the plunger 26 into the groove 20, until the lever 12 has been completely lowered and the pin is therefore in proper position for driving or forcing through the crimp of the superposed sheets. To perform this function, in the present disclosure, the slide 23 is provided with downwardly projecting longitudinal flanges 32 received in notches 33 in the upper side of the pin-receiving plate 19, one of said flanges acting as a gate and normally closing the groove 20 against entrance of the plunger 26. By the time lever 12 has been completely lowered however, the flanges move forwardly from the groove as seen in Fig. 3, thereby allowing operation of the plunger 26.

20 Further provision is made to prevent return of the plunger 23 to receive another pin, if the pin previously positioned in the groove 20 has not been driven. In the present showing, this function is performed by a lug 34 projecting downwardly from the slide 23 into a groove 35 in the upper side of the pin-receiving plate 19. When 25 the parts are at rest and groove 20 is empty as seen in Fig. 2, the lug 34 is behind the groove as illustrated in this view. As the machine is operated and the slide 23 moves forwardly to position a pin in the groove 20, the lug 34 moves across said groove prior to such pin positioning. Thus, 30 when the pin drops into the groove from the slide, the lug 34 is in advance of this pin, as seen in Fig. 3. Consequently, the lug 34 will strike the pin and lock the slide and the lever against return to normal position until said pin has been driven.

35 The pin outlet slot 18 in the hopper 17 is preferably disposed in the lower front corner of the latter, and the front wall of the latter is provided with a portion 36 which overhangs said slot, providing an inwardly opening groove 37 into which one or more of the pins must enter before one of them can drop into said slot 18. Spaced lugs 38 are provided on the upper side of the slide 23, movable into and from slots 39 in the hopper 17, to push a number of the pins gently toward the groove 37, when said slide 23 moves forwardly with respect to said hopper, thereby insuring that one or more of said pins shall enter said groove. Upon the front portion of the slide 23, two additional upstanding rearwardly beveled lugs 40 are provided, movable into notches 41 in the front wall of the hopper 17 to gently lift the pin or pins in the groove 37, when the slide moves rearwardly with respect to the hopper.

50 By providing the overhanging wall portion 36, the groove 37, the lugs 38 and the lugs 40, only a few of the pins can gather over the slot 18 and there is little likelihood of any of the pins becoming disarranged or sticking and failing to enter said slot 18. Moreover, it is insured that even if there be only one pin in the groove 37, it shall enter the slot 18.

55 Secured upon the base 10, is a longitudinal rib 42 having an upwardly open groove 43 which is aligned with the groove 20 and the openings 21 and 22, when the lever 12 is depressed, as seen in Figs. 4 and 5. Portions of the superposed sheets are laid upon this rib before depressing the lever 12, and one of the side members 14 of the latter is provided with an appropriately shaped flange 44 which co-operates with said rib in forming the sheets with arched formations 45, through which the pin 46 is driven upon operation of the plunger 26. A portion 47 of one of the lever side members 14 also assists in impart-

ing the arched formation 45 to the sheets. The lever portion 44 is of course formed with a suitable notch 48 which clears the pin 46 when the lever 12 is again raised after completion of the pinning operation.

60 A longitudinal finger 49 is secured at one end upon the base 10, the greater part of said finger being spaced above said base and serving to support one or more of the upper sheets above the remainder of said sheets, as will be clear from Figs. 4 and 5, it being of course understood that most of the sheets are inserted under this finger before being placed over the rib 42, whereas the upper sheet or sheets are placed over said finger. By the provision of this finger, when the lever portion 44 descends, it not only produces the arched formation 45 in all of the sheets but it produces a channel formation 50 in the sheet or sheets passing over the finger 49. When the pin 46 is driven, it passes through both the arched and the channel formations of the sheets so that the pointed end of the pin is received between the lower and the upper sheets, as illustrated in Fig. 5. Thus, when the sheets are removed from the machine, the pin point is so positioned that there is no danger of it injuring any person handling the pinned sheets and no danger of it catching into apparel, or any other articles into contact with which the pinned sheets may be moved.

65 It will be seen from the foregoing that in order to pin a plurality of sheets together, it is simply necessary to place the latter upon the rib 42, placing an upper sheet or sheets over the finger 49, depress the lever handle 13 until the parts reach the limit of their downward movement, and then inwardly push upon the plunger 26. When this plunger is released, it automatically returns to retracted position and when the lever handle 13 is released, the spring 16 restores the various other movable parts to their normal positions, in readiness for further use. The opening 22 and notch 48 clear the driven pin as the lever 12 returns to its normal raised position.

70 I claim:—

1. In a pinning machine, a base, a lever above said base, fulcrum means mounting said lever on said base for upward and downward swinging, a pin hopper carried by said lever, a pin receiver carried by said lever, a slide for feeding pins from said hopper to said receiver, means mounting said slide in operative relation with said hopper, means pivotally connecting said slide with said base on an axis vertically spaced from the axis of said fulcrum means to effect movement of said slide when said lever is operated, a plunger carried by said lever for forcing pins from said pin receiver, and co-acting means on said base and lever for crimping sheets in position to allow said plunger to force a pin through the crimp from said pin receiver.

75 2. In a pinning machine, a base, a lever above said base, fulcrum means mounting said lever on said base for upward and downward swinging, a pin hopper carried by said lever, a slide for feeding pins from said hopper, means mounting said slide in operative relation with said hopper, and means pivotally connecting said slide with said base, the axes of said fulcrum means and said connecting means being parallel and spaced apart to cause movement of said slide with respect to said hopper when said lever is swung about said fulcrum means.

80 3. In a pinning machine, a base having an upstanding post, a lever fulcrumed at one end to

- 5 said post and having a handle at its other end by means of which it may be depressed, a pin hopper carried by said lever, a slide for feeding pins from said hopper, means mounting said 5 slide in operative relation with said hopper, and means pivotally connecting one end of said slide with said post on an axis below and parallel with the axis of the lever fulcrum, the spacing of said axes serving to effect movement of the slide with 10 respect to the hopper when said lever is swung about said fulcrum.
- 15 4. In a pinning machine, a base provided with two laterally spaced upstanding posts, a lever over said base having a handle at one end and provided with two laterally spaced arms extending to its other end, fulcrum means connecting the free ends of said arms to said posts respectively, a pin hopper mounted between said arms, a slide under said hopper for feeding pins 20 therefrom, means for guiding said slide in operative relation with said hopper, and means pivoting one end of said slide between the lower ends of said posts, the spacing of said pivoting means below said fulcrum means causing operation of 25 said slide when said lever is operated.
- 30 5. In a pinning machine, a base provided with two laterally spaced upstanding posts, a lever over said base having a handle at one end and provided with two laterally spaced arms extending to its other end, fulcrum means connecting the free ends of said arms to said posts respectively, a pin hopper mounted between said arms, a pin receiver fixedly mounted between said arms and disposed under said hopper, a slide for feeding pins to said receiver from said hopper, said 35 slide being slidably received between said hopper and said pin receiver, and means pivoting said slide between the lower ends of said posts to effect operation of said slide when said lever is 40 operated.
- 45 6. In a pinning machine, a pin hopper having a pin outlet slot in its bottom, a pin-receiving member spaced slightly below said hopper and having a pin-receiving groove laterally spaced from said pin outlet slot, a slide mounted between said pin-receiving member and said hopper bottom, said slide having a slot adapted to receive a pin from said pin outlet slot and to drop said pin into said groove, a pin-driving 50 plunger mounted for movement into said groove, and a gate fixedly carried by said slide for closing 55

- said groove against entrance of said plunger until the slide has moved sufficiently to deliver the pin to said groove.
7. In a pinning machine, a pin hopper having a pin outlet slot in its bottom, a pin-receiving member spaced slightly below said hopper and having a pin-receiving groove laterally spaced from said pin outlet slot, a slide mounted between said pin-receiving member and said hopper bottom, said slide having a slot adapted to receive a pin from said pin outlet slot and to drop said pin into said groove, and a downwardly projecting lug on said slide adapted to strike the pin in said groove to prevent return of said slide to pin-receiving position until the groove-contained pin has been forced from the groove.
8. In a pinning machine, a pin hopper having a bottom and side walls, said bottom having a pin-discharge slot at the lower end of one of said side walls, said one wall being provided with a portion projecting inwardly beyond said lower end of said one wall and overhanging said slot; said overhanging wall portion, said lower end of said one wall and the portion of said bottom under said overhanging wall portion forming a groove which opens away from said one wall, said groove being of a size to receive a plurality of pins; a slide under the hopper having means to receive and carry a pin from said slot, and means on said slide for pushing a plurality of pins toward said groove when the slide is moved in one direction.
9. In a pinning machine, a pin hopper having a bottom and side walls, said bottom having a pin-discharge slot at the lower end of one of said side walls, said one wall being provided with a portion projecting inwardly beyond said lower end of said one wall and overhanging said slot; said overhanging wall portion, said lower end of said one wall and the portion of said bottom under said overhanging wall portion forming a groove which opens away from said one wall, said groove being of a size to receive a plurality of pins; a slide under the hopper having means to receive and carry a pin from said slot, means on said slide for pushing a plurality of pins toward said groove when the slide is moved in one direction, and means on said slide for slightly lifting the pins in said groove when the slide is moved in the other direction.
- JOSEPH E. HIGGINS.
